UNITED STATES PATENT OFFICE.

ELMER O. BEARDSLEY, OF CHICAGO, AND WALTER F. PIPER, OF OAK PARK, ILLINOIS,
ASSGINORS TO THE BEARDSLEY & PIPER COMPANY, OF CHICAGO, ILLINOIS, A
CORPORATION OF ILLINOIS.

MOLDING MACHINE.

Application filed July 25, 1921, Serial No. 467,290. Renewed September 21, 1922. Serial No. 539,622.

To all whom it may concern:

Be it known that we, ELMER O. BEARDSLEY and WALTER F. PIPER, both citizens of the United States, and residents of Chicago, in the county of Cook and State of Illinois, and Oak Park, in the county of Cook and State of Illinois, respectively, have invented certain new and useful Improvements in Molding Machines, of which the following is a full, clear, and exact description.

The invention relates to molding machines and more particularly to that type in which the molding machine and sand-elevating and feeding mechanism therefor are mounted on a truck to supply the machine with sand from a pile on the foundry floor.

One object of the invention is to provide an improved portable molding machine in which the mechanism for propelling the machine over the pile of sand is not mounted on, but is controllable from, the truck.

Another object of the invention is to provide an improved propelling mechanism for a truck on which the molding machine and sand-elevator are mounted.

A still further object of the invention is to provide improved propelling mechanism which is adapted to individually or simultaneously operate a plurality of machines over the molding machine room floor.

The invention consists in the several novel features hereinafter set forth and more particularly defined by claims at the conclusion hereof.

In the drawings: Fig. 1 is a side elevation of a machine embodying the invention, parts being shown in section. Fig. 2 is a section taken on line 2-2 of Fig. 1. Fig. 3 is a side elevation, showing the mechanism for driving the sand-conveyor. Fig. 4 is a view, partly in section and partly in plan, of a series of machines and the propelling mechanism therefor.

The invention is exemplified in a foundry equipment comprising a series of trucks 4 arranged transversely of one another, each adapted to be propelled over the floor of a molding-room on which the sand is arranged in piles or wind-rows. The trucks and molding machines thereon are alike in

construction so that a description of one will be applicable to all.

Each truck comprises a frame made up of sides 5 and tubular cross-members 6 and 7 which are rigidly secured to the frame-sides in suitable manner. The truck is movably sustained by rear carrying wheels 8 which are cross-connected by a shaft 9 extending through the tubular member 6 and a pair of front carrying-wheels 10 suitably journalled on the frame-sides 5 respectively. A molding machine 11 of any suitable type is secured to a base 12 which is secured to the tubular members 6 by U-bolts 13 and to a bracket 14 which is secured by U-bolts 15 to the tube 7. The molding machine mounted upon the truck may be of any suitable construction, so a detailed description thereof is not herein given. The molding machine illustrated is of the construction set forth in an application filed by us March 14, 1921, Serial No. 452068, to which reference may be had for a detail description thereof.

A cross-shaft 16 is journalled in the frame-sides 5 and is provided with spiral conveyor-blades 17 and 18 which are adapted to disintegrate the sand on the floor and convey it inwardly to a central elevator which comprises an endless chain 19 and buckets 20 which are adapted to scoop up the sand fed thereto by the conveyors 17 and 18 and to discharge the sand into a chute 21 from which it is discharged into the conveyor 22 which receives the sand for delivery to, and use in, the molding machine on the truck. This conveying and elevating mechanism serves to keep the molding machine continuously supplied with sand from the pile on the floor. The lower portion of the chain 19 passes around a sprocket 24 on the shaft 16 and its upper end passes around a sprocket 25 on a shaft 26 mounted in bearings 27 on a standard 28 which is secured to the bracket 14. An electric-motor 29 mounted on the truck drives a gear 31 on the conveyor-shaft 16 through a pinion 30 on the motor-shaft which meshes with an idler 32 which is fixed to a pinion 32^a which meshes with gear 31. In the operation of the machine, the cross-conveyors 17, 18 disintegrate the sand and

convey it transversely to the elevator buckets 20 which elevate the sand and deliver it to the feeding devices for use in the molding machine on the truck.

- 5 In order to keep the cross-conveyors supplied with sand, it is necessary to progressively propel the truck over the foundry floor and, for this purpose, a windlass or drum 33 is provided for each truck 4. Each 10 drum 33 is adapted to wind up a cable or flexible element 34, one end of which is attached thereto and the other end of which is connected, as at 35, to the truck, so that when the drum 33 winds up the cable attached thereto, the truck attached to the cable will be advanced into the pile of sand. Each drum 33 is mounted on a shaft 36 which is mounted in a frame 37. A ratchet wheel 38 is rigid with each drum 33. A dog 20 39 engages the ratchet 38 to prevent reverse rotation of the drum. The mechanism for conjointly operating the winding drums 33 of the series comprises a shaft 40 which is disposed at one end of the molding room and 25 is constantly driven at a reduced speed from an electric motor 41 by a pinion 42 on the motor shaft which meshes with a large gear 43 on the shaft 40. An eccentric 44 for each drum 33 is fixed to the shaft 40 and a pawl 30 45 is operatively connected to each eccentric. Each pawl 45 is adapted to operate one of the ratchets 38 and is positioned normally so it will be disengaged from the ratchet, its free end resting on a roller 46 so that the operation of the pawl will not operate its ratchet. The path of movement of each pawl is controlled by an electric-magnet which comprises a solenoid 48 and an armature 49 which carries a roller 50 adapted to lift 35 40 and hold the pawl 45 into operative relation with its ratchet 38 to operate the drum 33 when desired. Normally, when the coil is de-energized, the armature 49 will be lowered so that the free end of the pawl 45 will 45 rest on the roller 46 and be inoperative to rotate the ratchet 38. When, and so long as the coil 48 is energized, the armature 49 will hold the pawl 45 elevated to cause the ratchet 38 and drum 33 to be advanced step 50 by step from the shaft 40. A switch 51 suitably mounted on the truck is electrically connected by suitable flexible conductors 52 and 53 to the coil 48 so that the operator of the machines can easily control the advance 55 of the machine from a point adjacent the truck. Each operator can individually control his machine independently of the others. The invention exemplifies propelling mechanism for a portable molding machine 60 which is mounted on the molding room floor and which is easily controlled by the operator of the machine; which is simple in construction and is adapted to operate a plurality of machines from a single motor.

The invention is not to be understood as 65 restricted to the details set forth, since these may be modified within the scope of the appended claims, without departing from the spirit and scope of the invention.

Having thus described the invention, 70 what we claim as new and desire to secure by Letters Patent, is:

1. In apparatus for making moulds, the combination of a portable truck, a molding machine mounted on the truck, means for conveying sand from the floor and elevating it for use in the machine, and means for propelling the truck comprising a cable connected to the truck and stationary mechanism for winding the cable to advance the 80 truck.

2. In apparatus for making moulds, the combination of a portable truck, a molding machine mounted on the truck, means for conveying and elevating sand from a pile 85 on the floor for use in the machine, means for propelling the truck comprising a cable connected to the truck and stationary mechanism at one end of the molding room for winding the cable to advance the truck and 90 means on the truck for controlling the operation of the winding means.

3. In apparatus for making moulds, the combination of a portable truck, a molding machine mounted on the truck, sand-elevating and conveying mechanism mounted on the truck, mechanism for propelling the truck, comprising a pawl and ratchet and electro-magnetic means for controlling the operation of the pawl by the ratchet. 95

4. In apparatus for making moulds, the combination of a portable truck, a molding machine mounted on the truck, sand-elevating and conveying mechanism mounted on the truck, mechanism for propelling the truck comprising a cable, a drum for winding up the cable and a pawl and ratchet for operating the drum, and electro-magnetic means for controlling the operation of the ratchet by the pawl. 105

5. In apparatus for making moulds, the combination of a portable truck, a molding machine mounted on the truck, sand elevating and conveying mechanism mounted on the truck, mechanism for propelling the truck comprising a pawl and ratchet, a motor for operating the pawl, said pawl being normally inoperative to drive the ratchet, and electro-magnetic means for rendering the pawl operative to drive the ratchet. 115

6. In apparatus for making moulds, the combination of a portable truck, a molding machine mounted on the truck, sand elevating and conveying mechanism mounted on the truck, driving mechanism for the elevating and conveying mechanism mounted on the truck, means for propelling the truck comprising a cable connected to the truck 125

and stationary mechanism at one end of the molding room for winding the cable to advance the truck, and controlling means for said operating mechanism.

5 7. In apparatus for making moulds, the combination of a portable truck, a molding machine mounted on the truck, sand conveying and elevating mechanism mounted on the truck, driving mechanism for the conveying and elevating mechanism mounted on the truck, means for propelling the truck comprising a cable connected to the truck and stationary mechanism at one end of the molding room for winding the cable to advance the truck, and controlling means on the truck for said operating mechanism.

10 8. In apparatus for making moulds, the combination of a portable truck, a molding machine mounted on the truck, sand conveying and elevating mechanism mounted on the truck, driving mechanism for the conveying and elevating mechanism mounted on the truck, means for propelling the truck comprising a cable connected to the truck and stationary mechanism at one end of the molding room for winding the cable to advance the truck, and electrical controlling means for said operating mechanism.

15 9. In apparatus for making moulds, the combination of a portable truck, a molding machine mounted on the truck, sand conveying and elevating mechanism mounted on the truck, means for propelling the truck comprising a cable connected to the truck, a stationary drum for winding up the cable, pawl and ratchet mechanism for operating the drum and means for controlling the pawl and ratchet mechanism.

20 10. In apparatus for making moulds, the combination of a portable truck, a molding machine mounted on the truck, sand-conveying and elevating means on the truck, driving mechanism for the conveying and elevating means mounted on the truck, means for propelling the truck comprising a cable connected to the truck, a stationary drum for winding up the cable, a stationary motor, pawl and ratchet mechanism between the drum and the motor, and means on the truck for controlling the pawl and ratchet mechanism.

25 11. In apparatus for making moulds, the combination of a portable truck, a molding machine mounted on the truck, sand conveying and elevating means on the truck, driving mechanism for the conveying and elevating means mounted on the truck, means for propelling the truck comprising a cable connected to the truck, a stationary drum for winding up the cable, a stationary motor, pawl and ratchet mechanism between the drum and the motor, and electro-magnetic means on the truck for controlling the pawl and ratchet mechanism.

30 12. In apparatus for making moulds, the combination of a portable truck, a molding machine mounted on the truck, sand elevating and conveying mechanism mounted on the truck, and means for propelling the truck comprising a cable connected to the truck, a stationary motor, a shaft connected to be constantly driven by the motor, a stationary drum for winding up the cable, and electro-magnetically controlled mechanism for operating said drum from the shaft. 75

35 13. In apparatus for making moulds, the combination of a portable truck, a molding machine mounted on the truck, sand conveying and elevating mechanism mounted on the truck, and means for propelling the truck comprising a cable connected to the truck, a stationary motor, a shaft connected to be constantly driven by the motor, a stationary drum for winding up the cable, a pawl and ratchet for operating the drum 85 from said shaft, and electro-magnetic means for controlling the operation of said pawl and ratchet.

40 14. The combination of a plurality of portable trucks, a molding machine, sand-elevating and conveying mechanism mounted on each truck, a cable for each truck, a drum for winding up each cable, a stationary motor, mechanisms for separately operating the drums by power from said motor, and means 90 for separately controlling said operating mechanisms.

45 15. The combination of a plurality of portable trucks, a molding machine, sand elevating and conveying mechanism mounted 100 on each truck, a cable for each truck, a drum for winding up each cable, a stationary motor, a shaft constantly driven by said motor, mechanisms for separately operating the drums from said shaft, and means for 105 separately controlling said operating mechanisms.

50 16. The combination of a plurality of portable trucks, a molding machine, sand elevating and conveying mechanism mounted 110 on each truck, a cable for each truck, a drum for winding up each cable, a stationary motor, separate pawl and ratchet mechanisms for operating the drums respectively from the motor and electro-magnetic means for 115 controlling the operation of said operating mechanism respectively.

55 17. The combination of a plurality of portable trucks, a molding machine, sand elevating and conveying mechanism mounted 120 on each truck, a cable for each truck, a drum for winding up each cable, a stationary motor, a shaft constantly driven by said motor, separate pawl and ratchet mechanisms for operating the drums from the 125 shaft, and electro-magnetic means for controlling the operation of said operating mechanisms respectively.

18. The combination of a plurality of portable trucks, a molding machine, sand elevating and conveying mechanism mounted on each truck, a cable for each truck, a drum for winding up each cable, a stationary motor, a shaft constantly driven by said motor, separate pawl and ratchet mechanisms for operating the drums from the shaft, electro-magnetic means for controlling the operation of said operating mechanisms, and 10 switches on the trucks for controlling said electro-magnetic means.

ELMER O. BEARDSLEY.
WALTER F. PIPER.
